LOCK OF THE KEYLESS TYPE

Filed May 2, 1923

UNITED STATES PATENT OFFICE.

JOHN B. LAFOREST, OF DETROIT, MICHIGAN.

LOCK OF THE KEYLESS TYPE.

Application filed May 2, 1923. Serial No. 636,268.

To all whom it may concern:

Be it known that I, JOHN B. LAFOREST, a subject of the King of Great Britain, residing at Detroit, in the county of Wayne and State of Michigan, have invented certain new and useful Improvements in Locks of the Keyless Type, of which I declare the following to be a full, clear, and exact description.

10 This invention relates to locks and more specifically to that type of locks which do not require keys to open same but are adapted to be opened by setting an external operating knob to predetermined positions 15 as an incident to unlocking the same.

Such locks are known as the combination type, and it is the object of the present invention to provide an improved construction which will be simple in construction, 20 require few parts, effective in operation and afford a maximum protection against any fraudulent attempt to tamper with the same.

The principal object of the present invention is to improve the construction of the 25 lock shown and described in my copending application bearing Serial Number 616,854, filed February 3rd, 1923.

Although I have shown my invention applied to a particular lock, it is to be understood that the invention is capable of being used in connection with other locks, and that the drawings are merely illustrative and are not to be construed as defining the limits of the invention.

35 One object of the present invention is to provide an improved construction of the setting members, or tumblers, whereby their manufacture is facilitated and with minor changes may readily be formed so that a 40 large number of combinations is possible with a relatively few parts.

The arrangement and construction of the tumblers themselves is novel being so designed that they can easily be machined 45 and quickly assembled. One of the tumblers acts as a support for the remaining tumblers and when assembled together with the supporting shaft and knob the components are as a unit and may readily be inserted within the casing with a minimum 50 of effort.

Still another object of the present in-

vention is to attach the setting members and associated parts to the frames in such a manner as to require a minimum of space 55 permitting a compact arrangement, thereby enhancing the external appearance of the lock.

With these and incidental objects in view the invention consists of certain novel features of construction and combination of parts, the essential elements of which are set forth in the appended claims, and a preferred embodiment of which is herein-after described with reference to the drawings which accompany and form a part of the specification.

Of such drawings:

Figure 1 is a front elevation of the lock to which my invention has been applied. 70

Figure 2 is a view in side elevation.

Figure 3 is a sectional view taken on the line 3—3 of Figure 2 some of the parts being shown in elevation.

Figure 4 is an enlarged view of the un- 75 derside of the setting knob.

Figure 5 is a collective plan view of the three setting elements comprising part of my invention.

Figure 6 is a collective view, one in plan 80 and the remaining sectional views of the same parts illustrated in Figure 5.

Figure 7 is a central sectional view of the setting knob also showing a portion of the central supporting shaft. 85

Figure 8 is a sectional view taken on the line 8—8 of Figure 1 showing part of the interior mechanism.

As illustrated and described in my copending application the various mechanisms 90 which comprise the lock are carried by a casing indicated generally by a reference character 5. The said casing is formed with an aperture 6 (best shown in Figure 8) extending partly through and within 95 which is rotatably mounted the setting elements which will be described more in detail hereinafter. Slidably mounted in a vertical aperture 7 is one end of the shackle 8 the other portion of which registers with 100 a similar aperture 9 also formed in the casing 5.

Normally the shackle 8 is locked against movement but under certain conditions it

may be given a vertical movement sufficient to withdraw the shackle 8 from the aperture 9 permitting the said shackle to be rotated to effect its disengagement from the 5 casing in a manner well known in the art.

In order to limit the upward movement of the shackle 8 and to prevent the same from being completely drawn from the casing I have provided one end of the shackle 10 8 with a reduced portion 10 co-operating with a pin 11 passing through the casing 5 as is best seen in Figure 2.

As previously stated there is provided a plurality of setting elements 12, 13, and 15 14 which are rotatably mounted in the central aperture 6. In the present instance three have been shown but it is to be understood that this number is not the essence of the invention, and can be increased, 20 or even decreased, to meet the exigencies of a particular requirement.

The external setting knob 15 is provided with a flange 16 extending into the aperture 6. Passing through the said knob and 25 casing is a supporting shaft 17 for the setting elements 12, 13, and 14 provided with head portion 18 (best shown in Figure 7).

The opposite end of the shaft passes 30 through the casing 5 and is upset at its extreme end so as to prevent its withdrawal from the casing. The particular portion of the casing which receives the end of shaft 17 is dimensioned to receive the same and after the shaft has been secured in the casing 5 the recess is filled in with metal by a welding operation thereby concealing the joint and eliminating any visible external sign of the point of assembly.

Upon the front surface of the casing 5 40 there is engraved or otherwise formed a series of equal graduated marks encircling the flange portion 20 of the knob 15 and running from 0 to 40. A cut in the flange 20 of the knob 15 serves as a means to indicate the relative position of the knob and to assist the operator in determining the proper position of the same to release the lock.

As clearly shown in Figure 3 there is provided 50 a floating pin 21 which is slidably mounted in a horizontal passage 22 formed in the casing 5. The floating pin terminates at one end in a V shape and is adapted to register with a similar shaped cut in the lower end of the shackle 8. The opposite end is substantially semi-circular in section, flat at the end and is at times either adapted to co-act with the periphery of each of the setting elements 12, 13, and 14, or be received by the square notches 24 cut in the peripheries of the said setting elements.

The width of the pin 21 is substantially 60 equivalent to that of the aggregate thickness of the three setting elements, and semi-circular in shape; a small lug or pin 21' is

projecting from the casing just under the flat portion of pin 21 to prevent this latter from turning about its axis and from what has just been stated it will be evident that in order to lock the shackle 8 the V shaped end of the pin must be received by the notch formed in the shackle and the opposite end of the pin bear against the circular portion of the periphery of one or all of the setting elements. 70

In order to unlock the shackle all that is necessary is to adjust the setting elements in such a manner that the flat end of the pin 22 be received by the notches of all the setting elements whereby an upward movement of the shackle will cam the floating pin 22 forward thereby locking the setting elements against further movement until the shackle is re-instated. 75

In my previous application I disclosed a 80 floating pin slidably mounted in a horizontal aperture the axis of which passed through the center of the supporting shaft. In the present application this aperture is substantially horizontal but at a distance 90 from the said axis. By disposing this aperture in the aforesaid manner I have greatly reduced the size of the casing which carries these parts and have provided a very compact arrangement of parts. 95

It will be advantageous and helpful at this time to explain in detail the organization and novel construction of the setting elements 12, 13, and 14 and their relation to each other. 100

The setting element 12 is provided with an extending hub 26 through which the supporting shaft 17 passes and two laterally extending pins 27 and 271 which are radially the same distance from the center of 105 the shaft 17 as a pin 28 carried by knob 15 and adapted to co-operate therewith. Mounted on the hub 26 and in juxtaposition to the last mentioned setting element 12 is an intermediate setting element 13 110 which is also provided with a plurality of pins 29 and 291.

Attached to and movable with the hub 27 is a radially projecting member 30 which is adapted to engage either of the pins 29 or 115 291 carried by the element 13. The remaining element 14 is also mounted upon the hub and likewise carries a pin 31 in the path of the radially disposed projection 30. As shown in Figures 5 and 6 the opposite faces 120 of the elements 13 and 14 have suitable annular recesses 32 and 33 the aggregate width being greater than the thickness of the projection 30 to allow a free movement therein. To facilitate assembly of the element 13 upon the hub 27 the said element is formed 125 with a radial slot 34 (Figure 5) adapted to receive the projection 30 when the element 13 is passed over the said hub.

In order to retain the elements when set 130

in their adjusted positions I have provided a spring pressed plunger 35 bearing against the periphery of the setting elements. This construction is old and it is believed not 5 necessary to describe it in detail.

The general organization, construction and relation of the various components have thus been set forth in detail and the general operation of the lock to release the shackle 10 will now be given.

It will be assumed that the shackle has been reinstated and that the floating pin is in a position to prevent its upward movement.

15 One possible combination which has been shown is 11, 12 and 33, reversing the direction of rotation of the knob between successive settings.

As will be presently described, when the 20 shackle is reinstated the knob 15 is prevented from being rotated clock-wise (as viewed in Figure 3) and in order to lock the shackle the operator rotates it counter-clockwise, approximately a full revolution. In order to 25 unlock the shackle the knob is rotated clock-wise until the pin 28 engages the pin 27 and drives the same and the element 12. As the element 12 and the projection 30 are rotated the latter will engage the pin 31 and drive 30 the element 14 clockwise. At about the 11 mark the notch 24 of the element 14 will be in line with the floating pin. The knob 15 is now turned counter-clockwise first idly until the pin 28 strikes the pin 271 whereupon the projection 30 will strike pin 291 to rotate the element 13 counter-clockwise. At the 12 mark the notch 24 will now be in line with the floating pin. The knob is again turned clockwise whereupon the element 12 will 35 have, by virtue of the engagement of pin 28 with pin 27, been rotated sufficiently to bring the notch 24 in line with the floating pin. In the present instance this will take place at the 33 mark on the scale. The shackle may now be moved 40 outwardly to effect its disengagement from the casing. As the shackle is pulled outwardly the floating pin will be carried forwardly to bring the flat end in engagement with the square notches 24. When in this 45 position the setting elements are locked against movement. When the shackle is reinstated the setting elements can be rotated but in a particular direction only. In the 50 present instance, to lock the shackle the knob must be turned counter-clockwise as viewed in Figure 3. If an attempt is made to rotate the knob clockwise the horizontal edge of the square notch of one of the elements will 55 engage the underside of the floating pin and tend to lift it up, but this will be prevented as will readily be seen and understood. When an element is rotated counter-clockwise the vertical edge of the notch will con-

tact with the flat edge of the pin 21 and force 65 the latter rearwardly. Upon further rotation of a setting element the circular periphery of the same will contact with the floating pin 21 thereby locking the shackle. Prevention of the rotation of the setting elements 70 in a clockwise direction insures that the setting elements are adjusted in a manner to insure locking of the shackle and prevent any malaction of the setting elements and the knob.

75 As the position of the pins carried by the setting elements can be varied at will, it will be possible to obtain a great number of different combinations without effecting the form of the setting elements.

80 From the foregoing description taken in connection with the accompanying drawings it will be manifest that a combination lock is provided which will fulfill all of the necessary requirements of such a device, and it is 85 to be understood in this connection that various minor changes in the specific details of construction may be resorted to within the scope of the appended claims, without departing from the spirit or sacrificing any of 90 the advantages of the invention.

What is claimed is:

1. In a device of the class described, the combination of a plurality of setting elements one of which is formed with a hub on which are rotatably mounted the remaining elements, projections upon the said remaining setting elements, a radially disposed projection integral with the said hub, co-operating with the said projections, and annular recesses formed in the remaining setting elements to allow a free movement of the radially disposed projection.

2. In a device of the character described, the combination with a knob carrying a shaft, a setting element formed with a hub mounted on the shaft, a plurality of setting elements carried by the hub, a projecting member integral with said hub and a slot formed in one of the elements carried by the said hub adapted to receive the said projecting member whereby the assembly of the last mentioned element on the hub is facilitated.

3. In a device of the character described, the combination with a knob carrying a shaft, a projection carried by the said knob, a setting element formed with a hub mounted upon the said shaft, a projection carried by the said element engageable with the projection carried by the said knob, a plurality of setting elements mounted upon said hub, one being provided with a single projection while the other is provided with a plurality of projections, and a radially projecting member carried by the said hub engageable with the projections carried by the setting elements mounted upon the said hub.

4. In a device of the character described,

the combination with a knob carrying a shaft, a projection carried by the said knob, a setting element formed with a hub mounted upon the said shaft, projections carried by the said element engageable with the projection carried by the said knob, a radially projecting member integral with said hub, a

plurality of setting elements mounted on the said hub with annular recesses to allow a movement of the radially projecting member within the same, and projections carried by the last mentioned elements engageable with the radially projecting member. 10

JOHN B. LAFORST.
